2,265,874

CURTAIN STRETCHER

Alice Pearl Seidl, Van Nuys, Calif.

Application May 9, 1939, Serial No. 272,571

4 Claims. (Cl. 45—24)

This invention relates to means for stretching fabrics, curtains and the like and for holding them in stretched condition until set which is generally by drying.

The invention consists principally of a plurality of bars that are designed to grip the edges of the fabric in a manner not to harm it, all the bars of which are movable for adjustment vertically and horizontally so as to assure their parallelism and equal distribution of stresses in the fabric. The bars form a rectangular frame which are supported by straddle-legged supports at the ends of the frame.

The size of the stretching device will depend upon the type and kind of fabric and also its size. Although wood may be the present preferred material from which to construct the device, other materials may be used such as metal; some of the parts, however, may consist of cellulose compounds and their derivatives.

An object of the invention is to provide a frame for stretching fabrics which is designed in a manner not to damage the same, and which can be economically constructed and sold to the trade at a low price.

Another object is to provide a rectangular frame for stretching fabrics, all sides of the frame being adjustable to assure parallelism and equal distribution of the stresses in the fabric.

Another object is to provide means for gripping the edges of the fabrics, the means being constructed of foldable parts which are designed to be clamped over the edge of the fabric, resilient means being combined with the parts to prevent damage to the fabric.

A still further object is to present a curtain stretcher into which the curtain can be easily and quickly adjusted in place and removed.

Other objects, advantages and features of my invention will appear from the accompanying drawing, the subjoined detailed description, the preamble of these specifications and the appended claims.

Applicant is about to illustrate and describe one of the forms of her invention in order to teach one how to make, use and vend the same, but it is to be understood that the drawing and description thereof are not to limit the invention in any sense whatsoever, except as limited by the appended claims.

In the drawing:

Fig. 1 shows the invention in front elevation.

Fig. 2 shows the invention in side elevation.

Fig. 3 shows a fractional part thereof enlarged.

Fig. 4 shows the left end elevational view of Fig. 1.

Fig. 4a shows an enlarged fractional view of a part of the invention.

Fig. 5 shows a plan view taken substantially on the line 5—5 of Fig. 1.

Numerals 1 and 2 represent spaced apart horizontal bars or beams which are adjustably attached to front upstanding legs 3 and 4. Each leg has a rear leg indicated by 5 movably attached to the front leg as by the hinge 6 for adjustable straddling support. The bottoms of the legs are provided with elastic or rubber non-skid tips 7. The front and rear legs are adapted to be spread apart as shown in Fig. 2 and are provided with a chain or wire 8 to prevent collapsing of the legged support. One end of each wire is provided with a screw-eye 9 fixed to the rear leg 5 and the other end of the wire is provided with an eyelet stem 10 which is adapted to be inserted into any one of a plurality of holes indicated at 11. By placing the stem of the eyelet 10 in the lowermost hole 11, the front and rear legs can be brought closer together than when the stem is placed in one of the higher holes. This adjustment obviates means for shortening the wire or chain 8.

The rear sides of the beams 1 and 2 are provided with guides 12 near their ends. The guides are merely offset metal plates having bores configurated to match the outer surfaces of the front legs. The guides are telescoped by the front legs, as shown, for sliding engagement. They have flanges 13 which are fastened to the rear of the beams by screws or any other means suitable for the purpose. The guides are provided with enlarged holes 14 along the sides thereof, and which are large enough to easily receive the stem of an eyelet 15, best shown in Fig. 5. The stem of the eyelet is of sufficient girth to snugly fit the holes 11 of the legs so that the guides and their respective beams can be securely held in any horizontal position along the front legs 3 and 4.

Each beam comprises two component parts 16 and 17 which are pivoted together by hinges 18 as shown. Along one edge of the part 16, is a strip of sponge rubber 19, which is glued or otherwise held thereto. The other component part 17 is provided with a frictional strip of metal or other material 20 along the edge thereof. The strip 20 has stamped therein small triangular projections 21 which are adapted to slightly embed themselves in the edges of the fabric to be

stretched. When the component parts 16 and 17 of the beams are firmly pressed against one another, with the edge of the curtain therebetween, resilient U-straps 22 are forced onto the beam as shown in Fig. 1. This securely holds the curtain so that the beams may be spread without any danger of the curtain slipping or being damaged.

The holes 11 along the sides of the legs are numbered, as shown in Fig. 4, so that the guide members 12, at the ends of either one of the beams can be adjusted to the proper hole in order to make certain that the beams are horizontal or in proper parallelism with one another.

Whenever the vertical edges of the curtain 23 are provided with open hems, as indicated by the numerals 24 and 24', vertical bars or flat rods 25 are inserted therein. These rods consist of two parts 25' and 25'' which are arranged in telescoping relation with one another so that they can be extended to a length almost the combined lengths of their component parts 25' and 25''. Since these sliding curtain rods are in common use, it is not seen necessary to further describe them. The ends of the rods are provided with bayonet slots 26. Near the longitudinal hinged edges of the portions 17 are provided rows of headed pins 27 which are adapted to receive the bayonet slots at the ends of the rods 25. The pins 27 are also numbered so that the rods can be vertically spaced along the beams and kept in parallelism with respect to one another.

To stretch the curtain 23 in the frame, rod 24' is first run through the open hem of the curtain and the slots at the ends thereof placed over the pins numbered 1 of the top and bottom beams, open position of beams 1 and 2 being assumed. The rod 24' is then run through the hem at the other vertical end of the curtain and its slots placed over the pin heads nearest approached after the curtain has been stretched horizontally. The pin numbers in this last instance may be, for instance, 40 in both upper and lower beams. Now, since the vertical edges are fixed to the frame, it is only necessary to lay the top edge of the curtain against the strip 20 as straight as possible and then close the beam so as to clamp the edge, and while holding in clamped position, to lock the folded beam by forcing thereon the U-straps 22.

The lower edge of the curtain is then placed in the lower open beam and then locked therein as in the manner set forth for the top beam operation. After the lower beam is firmly attached to the curtain edge, the beam is forced downwardly until the curtain is under proper tension, then locked in its downward position by inserting eyelet stems or pins 15 through the guides and into the proper or nearest hole 11 along the side of the front legs.

However, when one of the edges of the fabric is not provided with an open hem so as to receive a rod 25, a bar 28 is provided. The bar 28 is very similar to the beams 1 and 2 and comprise component parts 29 and 30 (see Figs. 4 and 4a) which are hinged together by the hinges 31. The upper end of the vertical bar 28 is provided

with a guide 32 which is attached to receive a strip 33 extending beyond the edge of the part 17 of the beam 1. A similar strip 34 is provided and extended beyond the end of the part 17 of the beam 2 against which merely rests the bottom end of the vertical bar 28. The adjacent ends of the parts 17 prevent the bar 28 from being pulled toward the opposite ends of the beams. The vertical bars 28 are adapted to be held in clamped position by resilient U-straps the same size as used on the beams. The part 30 of this vertical bar has fixed along one of the edges thereof a sponge rubber strip 35, and along the edge of the part 29 is a strip 36 having a plurality of slightly protruded triangular elements 37 like the ones described for the beams 1 and 2. The parts 29 and 30 of this bar are adapted to be clamped in locked position by the U-straps 22.

Whenever the vertical bar 28 is employed, obviously the rod 25 at the same end of the frame is removed. The bar 28 must be substituted for the rod 25 when there is no open hem at its end of the curtain. Obviously, a similar bar like 28 would be substituted for the other rod 25 at the other end of the frame should the device be used for stretching fabrics upon which there is no open hem whatever.

Having thus described my invention, what is claimed as new and desired to be secured by Letters Patent is:

1. In a fabric stretching device having supporting means, a frame for receiving the fabric comprising top and bottom horizontal beams and vertical bars, said beams comprising elongated hinged sections adapted to clamp the top and bottom edges of the fabric, said bars comprising telescoping sections having their ends clamped between the sections of said beams so that the beams can be vertically adjusted without disturbing said bars.

2. The device recited in claim 1 wherein the beams have strips of soft elastic material to prevent damage to the fabric when clamped in place.

3. The device recited in claim 1 wherein one section of each beam is provided with a roughened strip and the other section of each beam with an elastic strip so that fabric placed between the sections of the beams are resiliently forced into gripping relation with the roughened strip.

4. In a fabric stretching device having supporting means, a frame for receiving the fabric comprising top and bottom horizontal beams and vertical bars, said beams comprising elongated hinged sections adapted to clamp the top and bottom edges of the fabric, said bars comprising telescoping sections having their ends clamped between the sections of said beams so that the beams can be vertically adjusted without disturbing said bars, means extending beyond the ends of the beams, a vertical bar having hinged sections adapted to clamp the fabric along its vertical edges, one of the sections having top and bottom attaching elements for engaging the means extending from the beams.

ALICE P. SEIDL.
